(57) **CLAIM**

The ornamental design for bicycle protective cover, as shown and described.

DESCRIPTION

FIG. 1 is a perspective view of a bicycle protective cover in accordance with the present invention;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof; and,

FIG. 8 is a perspective view of the bicycle protective cover shown in FIG. 1 installed on a bicycle in a condition of use. The broken lines in the Figures show portions of the bicycle protective cover and environment which form no part of the claimed design.
